GARMENT

Eleanor Donaldson, Minneapolis, Minn.

Application November 10, 1932, Serial No. 641,961

3 Claims. (Cl. 2-226)

This invention relates to a garment and while the invention is applicable to various inner and outer garments, it is illustrated as applied to an under garment.

5 It is well known that when a garment is worn which fits with any degree of snugness, and the wearer bends forward, there is a tendency to stretch the garment in the rear, as the rear portion of the body lengthens in such bending or in 10 stooping, while the front part of the body is not lengthened. Unless extra length is provided in the rear of the garment, the garment tends to bind across the back and at the rear of the hips where the bending takes place. Such a severe 15 strain is sometimes put upon garments in this bending or stooping position, that they tear. Whenever the garment tends to stretch and there is not sufficient material to accommodate the bending, the garment will bind on the body and 20 cause discomfort.

It has been the usual practice to cut the back of the garments for the lower part of the figure longer than the front, in order to give the wearer 25 comfort and the garment a longer life. This method has to be followed when garments are made of inelastic or non-stretchable material. In this way comfort for the wearer is provided for and longer life of the garment is secured, but when the wearer of such a garment is standing 30 erect, there is an apparent excess of material in the back of the garment that many people find objectionable. This excess of material, of course, is used in the bending motions, but seems excessive when the body is upright.

35 The same problem is encountered in the leg portions of the garments at the knee. When the knee is bent, the garment tends to stretch over the front of the knee and unless fullness is provided, the garment will bind at the knee portion and cause discomfort.

It is an object of this invention, therefore, to provide a garment made of elastic material or material which has considerable stretch in one direction, the material being so disposed on the 45 garment that it can readily stretch at the points where stretching occurs in the bending movements of the body.

50 It is a further object of the invention to provide a garment made of material which has an appreciable stretch in one direction, such as woven or knitted material, which garment has the portion at the rear in the vicinity of the hips arranged so that it will stretch vertically and the portion at the front of the garment above the

knee being arranged vertically in the non-stretchable direction of the material.

It is a still further object of the invention to provide a garment having waist and leg portions, said garment being made of material which has appreciable stretch in one direction, but comparatively little stretch in a direction at right angles to said direction, the material at the rear and upper portion of the garment being arranged vertically in the first mentioned direction, while the material at the front and upper portion of the garment is arranged vertically in the second mentioned direction. 5

It is still another object of the invention to provide a garment having a waist portion and 15 leg portions which extend below the knee, said leg portions at the front of the knee and a short distance above and below the knee having the material arranged vertically in the direction of stretch thereof, while the portion in the rear of 20 the leg in the vicinity of the knee is arranged vertically in the direction of non-stretch of the material.

These and other objects and advantages of the invention will be fully set forth in the following description made in connection with the 25 accompanying drawing, in which like reference characters refer to similar parts throughout the several views, and in which:—

Fig. 1 is a view in front elevation of the garment, the same being shown on the wearer; 30

Fig. 2 is a view in rear elevation of Fig. 1;

Fig. 3 is a view of the garment shown on the wearer in stooping position, showing a modification; 35

Fig. 4 is a view in side elevation of the garment shown on an enlarged scale; and

Fig. 5 is a partial view in rear elevation of the garment shown on an enlarged scale.

Referring to the drawing, a garment is shown 40 comprising the waist portion 10 and leg portions 11, said garment being illustrated as an under garment. The said garment is made of material which is much more stretchable or expansible in one direction than it is in a direction at right angles to said direction. Some well known materials of this character are knitted and woven goods. Such latter goods have an appreciable stretch in a direction transversely of the direction of weave, but have comparatively little, if 45 any, stretch in a direction lengthwise of the weave. In the drawing, the closely adjacent and substantially parallel lines represent the ribs of the knitted or woven material, and the material is thus quite stretchable transversely of these 50 55

2

lines or ribs. These ribs, of course, extend in the direction of weave.

10 direction of weave. The garment at the rear from its top to a line 12 substantially at or a short distance below the crotch has the direction of stretch extending vertically, and this part of the garment which is designated 12a thus has the ribs extending transversely thereof. The front of the garment from the top to a line 13, which portion is designated as 13a, has the non-stretch direction extending vertically and the ribs of the material thus extend vertically in this portion. The portion of the garment at the rear below the line 12 and below the portion 12a has the material extending vertically 15 in the non-stretch direction and the ribs of the material thus extend vertically in this portion.

With this construction it will be seen that when the wearer bends forwardly at the waist or hips, the material will be extended as indicated by the diverging lines in the portion 12a in Fig. 3. As stated, this portion 12a can expand or stretch easily and readily and there is thus no binding of the material and no discomfort to the wearer. If the garment does not extend below the knees, it will be seen that such a garment would be extremely comfortable and no strain would be put on the material at the rear and neither would it be necessary to have any fullness or excess of material at the rear of the garment. Such a garment would be very suitable for short length underwear, bloomers, and similar garments.

garment, underwear, bloomers, and similar garments.

In the embodiment of the invention illustrated the leg portions 11 are shown as extending below the knee. The material at the front of the garment from a line 13 to a line 14, which is a short distance below the knee, is disposed in the direction of stretch, extending vertically so that the ribs extend transversely of the leg portions. A zone 14a is thus formed at the front of the knees which will readily stretch when the knee is bent so that there will be no binding of the material and no discomfort to the wearer. The front portion of the garment below the line 14 has the material extending vertically in the direction of non-stretch, and the ribs of the material thus extend vertically in this portion which is designated 15a. The rear portion of the legs 11 designated 16 as already stated, have the material extending vertically in the direction of non-stretch, so that the ribs extend lengthwise or vertically of the leg portions below line 12. In the embodiment of the invention illustrated the portions 12a, 13a, 14a, 15a and 16 are shown as connected at their edges.

55 In Fig. 3 the garment is shown as terminating by stitching 17 at the bottom of portion 14a.

at the bottom of portion 14a.
When the garment described is worn and the wearer bends forward, the stretchable material, such as the knitted or woven fabric which is usually quite soft, readily expands or stretches over the convex part of the body which is bent. This is true both at the rear and the hip portion of the body and at the front portion of the body at the knee zone. It will also be noted that the upper portion 18 of the crotch opening is of considerable width and due to the fact that the material stretches readily when the body is bent, as when bending over, stooping, or sitting, there will be no binding at the crotch. The formation of the crotch opening permits a wide movement of the legs and a wide separation thereof without any discomfort.

any discomfort. From the above description it will be seen that applicant has provided a simple and very comfortable garment. The principle of the in-

vention can be applied to all garments of all types for men, women and children, both the so-called "one-piece" or "combination" type, for the upper as well as the lower part of the body, and also garments of various lengths, designed for the lower part of the body alone. The invention can also be readily applied to bathing suits, pajamas, and similar articles of clothing. The invention will also find ready application in various outer knitted garments, such as knitted dresses, jerseys, and similar garments. It will be understood that zones 12a and 14a are representative of elastic material generally. It will thus readily be seen that the portions 13a, 16 and 18a could be made of a different inelastic material than the remainder of the garment. The invention, of course, can be readily applied to children's union suits constructed with the so-called "drop seat" and can also be readily applied to union suits of underwear for either men or women, provided with what is usually called a back opening. One great advantage of the present garment, of course, is that it can be made to closely fit the body and yet movements of the body are permitted without binding of the material, excessive strain being placed thereon, or discomfort being caused to the wearer. This would be true of garments with or without the rear opening. With the present garment a great excess of material is not necessary at the rear when an opening or closing flap is provided. Due to the ready stretching of the material, a back opening of lesser extent than is usually used, can be provided in a garment made according to applicant's invention, as the stretching of the material in the rear lengthens or increases the back opening. The stretchable portion of the garment also lessens the strain placed upon the other portions of the garment, so that no discomfort is experienced when the back opening is used. While the garment readily stretches in the desired portions to accommodate the various movements and shape of the body, it quickly assumes its normal shape when the body is erect or not in bending position. It will also be obvious that the stretchable portions can be provided to accommodate the curved convex portions of the body.

The device has been amply demonstrated in actual practice and found to be very successful and efficient.

and efficient. It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims. 55

what is claimed is:

What is claimed is:—
1. An undergarment for women having leg portions and a continuous unbroken close-fitting waist portion, said garment being made of one material which has an appreciable stretch in one direction but comparatively little stretch in a direction at right angles thereto, said garment having the material at the waist portion extending unbrokenly from one side of the garment to the other side, said material at the front being stretchable from side to side, said garment at the rear portion having said material extending unbrokenly from the crotch to the top of said garment and stretchable up and down, whereby said material at the rear will stretch to accommodate bending forwardly and

the material at the waist will stretch to permit entry into said garment.

2. A form-fitting undergarment having leg portions and a waist portion and made of substantially one thickness of material, which material has an appreciable stretch in one direction but no appreciable stretch in a direction at right angles thereto, said material at the rear portion of said garment from a transverse line approximately at the top of said leg portions extending unbrokenly from one side to the other thereof and to the top of said garment and stretchable up and down, said material at the front of said garment extending unbrokenly from side to side and from a line just above the knee and to the top of said garment and stretchable from side to side, said material at the rear below said line to the bottom of the leg portions being stretchable from side to side but at the front from said line just above the knee to a line just below the knee and from one side of the leg to the other being stretchable up and down.
3. A form-fitting undergarment having leg

portions and a closed continuous waist portion, said leg portions extending below the knee, said garment being made of one material having an appreciable stretch in one direction but comparatively little stretch in a direction at right angles to said direction, the material at the front of said garment from a line just above the knee to the top of the garment extending unbrokenly from one side to the other and being stretchable from side to side, the material at the rear of the garment from a line substantially at the crotch to the top of the garment extending unbrokenly from one side to the other and being stretchable up and down, said material at the rear of said leg portions below said line being stretchable from side to side, said material at the front of said garment from said line just above the knee to a line just below the knee extending unbrokenly from side to side and being stretchable up and down, said material below said line just below the knee to the bottom of the leg portions at the front being stretchable from side to side.
